(57) **CLAIM**

The ornamental design for a hinged lamp as shown and described.

DESCRIPTION

The patent or application file contains at least one drawing executed in color. Copies of this patent or patent application publication with color drawing(s) will be provided by the Office upon request and payment of the necessary fee.

1. Hinged lamp
1.1 : Perspective
1.2 : Perspective
1.3: Perspective in an alternate position
1.4 : Left
1.5 Partially enlarged
1.6 Partially enlarged in an alternate position
1.7 : Front
1.8 : Back
1.9 : Bottom
1.10 : Top
1.11 Partially enlarged
1.12 Partially enlarged in an alternate position
1.13 Partially enlarged in an alternate position
The design corresponds to a hinged lamp; the portions shown in yellow in figs. 1.2 and 1.9 represent illumination; the colours shown are not specifically claimed.
